SLIDING BED PRESS

John P. Singiser, Chicago, Ill., assignor to The American Laundry Machinery Company, Cincinnati, Ohio, a corporation of Ohio

Application August 2, 1933, Serial No. 683,322

19 Claims. (Cl. 68—9)

This invention relates to presses of the sliding or receding buck type, particularly, presses used in laundry and garment pressing establishments.

There are certain advantages in a press having a relatively fixed head and a bed or buck movable substantially horizontally from a position adjacent the operator and out of registration with the head where the lay of the work is arranged to a second position in registration with the head where the pressing operation takes place. This construction removes the heated head from the operator and, because of the receding movement of the buck, makes it less likely that the operator's hand will be caught between the buck and head when the press closes.

One of the objects of my invention is to provide a press of the type described in which all of the operations are performed by fluid pressure actuated means.

Another object of my invention is to provide improved automatic control means in which the operator actuates but one control member and thereafter the movement of the buck into registration with the head and the closing of the press occur automatically. In a similar manner, the actuation of one control member effectuates complete opening of the press.

Another object of my invention is to provide improved tandem control for a plurality of presses, whereby the operator at one machine may produce an operation at another machine.

A still further object of my invention is to provide a safety guard which both protects the operator's hands from injury and also forms a part of the fluid motor control means.

Other objects and advantages of my invention will be seen in the accompanying drawings and description and the essential features of which are summarized in the claims.

In the drawings, Fig. 1 is a side elevation partly in section along the line 1—1 of Fig. 3, parts being broken away to show the construction, the press in this figure is in the open position; Fig. 2 is a side elevation partly in section and similar to Fig. 1, showing the press in closed position; Fig. 3 is a front elevation with the front panel of the outer casing removed to show the mechanism; Fig. 4 is a plan view of the guard means and control lever mechanism; Fig. 5 is an enlarged section on the line 5—5 of Fig. 4; while Fig. 6 is a diagrammatic view of the control mechanism of two presses connected for tandem operation.

The embodiment of my invention illustrated comprises in general a stationary head and a

buck supported for substantially horizontal movement into and out of registration with the head. Any suitable fluid-actuated means is provided for moving the buck from open position into registration with the head and for closing the press. 5 In the drawings, I have shown two pistons in suitable cylinders, one piston and cylinder adapted to provide the horizontal movement of the buck and the other adapted to raise the buck against the head during the pressing operation. 10 The control mechanism comprises inlet and exhaust valves for the fluid pressure medium, one for each cylinder and piston combination. The controls governing the vertical movement of the buck are actuated by an interlock which can operate only when the buck reaches the registering position beneath the head. The control valves for the horizontal movement of the buck are connected with a guard depending in a position before the stationary head where the guard will 15 be contacted by the operator's hands if they are near to or resting upon the buck as it moves under the head. Such contact with the guard operates to return the buck to its open position, thus preventing injury to the operator. The 20 presses may be operated singly, but I have provided a fluid connection between two machines whereby the initiation of the horizontal movement of the buck toward the head in one press 25 also operates the release controls to open the other 30 press. The mechanism also includes devices for snubbing or cushioning the movement of the buck at the ends of its horizontal path, so that the 35 parts operate smoothly.

Hereinafter in the specification and claims the 35 term "translation" when used will indicate a substantially horizontal movement of the bed or buck into and out of registration with the head, and the term "reciprocation" will indicate movement of the pressing elements toward and from each 40 other in a generally vertical direction. The terms "horizontal" or "horizontally" will be used to indicate substantially horizontal movement.

The structure illustrated comprises a table 10 supported at the proper height above the floor on 45 a suitable framework including one or more C-shaped members 11 rigid with the table and supporting a pressing head 12 in a substantially horizontal position spaced above the table. The head, when used for pressing fabrics may be 50 heated in any manner known to the art. A pressing bed or buck 13 is mounted in a carriage 14 which in turn is provided with rollers 15 adapted to travel on rails 16 which are suitably carried by the table. The rollers 15 may be grooved to 55

coact with a V-shaped head on the rails 16 so as to maintain a straight path of travel without side motion during the translatory movement of the buck. The buck is also mounted for vertical movement relative to the carriage, such mounting including a downwardly extending stem 17 on the bed slideable in a correspondingly shaped opening in the carriage, relative rotation of the parts being prevented by dowel pin 90. The carriage is also provided with a suitable cam 18 having a notched portion 19 for automatic control of the closing of the press, as hereinafter described. The table 10 may be provided with upwardly extending side plates 42, from the upper edges of which flanges 43 extend inwardly to overlie the rollers 15. This prevents the carriage leaving the rails and guards the rollers.

It will be noted that the upper arms of the substantially C-shaped frame members support the head, while the lower arms are positioned to receive the reaction when the press is closed after the buck has been moved horizontally into the open side of the C. This provides a compact and economical construction, for the arms of the C-shaped frame confine the only major force involved in the production of pressure and the heavy frame parts may thus be reduced to these comparatively small members.

For providing horizontal movement of the buck into and out of registration with the head, I have shown a translation cylinder 20 suitably mounted in trunnions 21 carried by the machine frame, the cylinder having a suitable piston 22 for actuating the piston rod 23. The connections between the rod 23 and the carriage 14 comprise a swinging arm 24 pivoted to the frame of the machine at 25, a link 26, a crank 27 which is rigid with a shaft 28 extending transversely of the frame and rotatable therein, a pair of cranks 29, also rigid 40 on the shaft 28 and connected by suitable links, as at 30, with the carriage 14. While the cylinder might be double acting to provide movement of the buck both into and out of registration with the head, I have shown the mechanism arranged 45 to move the buck toward the closing position by power, and have provided a spring 31 for returning the buck to the open position. For this purpose the spring 31 is connected at one end to a crank arm 32 which is rigid with the shaft 28, and the other end of the spring is connected 50 by a cable 33 to a drum or shaft 34. Provision is made for adjusting the tension of the spring, as by ratchet and pawl mechanism 35, whereby more or less of the cable may be wound about the 55 shaft 34, as desired.

For snubbing or cushioning the movement of the carriage at the opposite ends of its travel, there is shown a double acting snubber 36 mounted on the base plate of the frame and connected 60 by suitable linkage 37, 38 to a crank arm 39 rigid with the shaft 28. An adjustable stop 40 may be provided on the buck carriage which is adapted to engage a boss 41 on the arm 11 to limit the rearward movement of the buck.

Vertical reciprocation of the buck to close and open the press is accomplished by a piston having a shorter stroke and a greater area than the piston for translatory movement, so as to provide the greater power necessary for the pressing operation with economy of motive fluid. I have shown a cylinder 44 mounted beneath the table 10 and provided with a suitable piston 45, which has a rod 46 adapted to extend through an opening 47 in the table to contact the stem 17 of the buck 75 when the pressing elements are in registration.

Fluid pressure applied below the piston 45 will then raise the buck in its carriage 14 and press the buck against the head. The controlling means for the fluid supply to cylinder 44 is illustrated as an inlet valve 48 and an exhaust valve 49 connected to the cylinder by a common conduit 50.

Means is provided for preventing pressure operation of the piston 45 except when the pressing elements are in registration. In the embodiment disclosed this takes the form of a mechanical interlock between the buck carriage and the control valves for the piston. This interlock comprises a control arm 51 pivoted to the frame and having lateral extensions adapted to actuate the valves 48 and 49. A spring 52 serves to bias the arm in a clockwise direction, Fig. 1, but the follower 53 carried by the arm is normally depressed by the lower edge of cam 18 to hold exhaust valve 49 open and inlet valve 48 closed. When the 20 pressing elements reach the registering position (Fig. 2), follower 53 rises in the notch 19, whereupon spring 52 actuates the arm 51 in a clockwise direction, thus reversing the position of valves 48 and 49 and closing the exhaust and admitting 25 pressure to cylinder 44 to raise piston 45.

The control mechanism is shown arranged for either individual press operation or for operating two presses in tandem, in which latter case the operator works two presses alternately and the 30 act of closing one press opens the other so that it is ready for her before she reaches it.

The arrangement for individual operation comprises in general a weighted member adapted to swing freely and to be held normally retracted 35 and which by its movement controls the operating valves for the translation motor. Swinging freely it causes actuation of the motor for closing, and when retracted it causes the motor to operate for opening. I take advantage of this 40 arrangement to utilize the weighted member as a safety guard for the operator. To this end it depends before the head in such position that hands lying on the buck as it recedes must necessarily strike the guard and carry it to retracted 45 position, thus opening the press. This guard has a detachable connection with linkage which normally holds it in retracted position in all positions of the pressing elements except registration. This linkage is connected with the cam and follower parts 53, 18 already described as part of the control means for the reciprocation cylinder. An operator-operated lever serves to disconnect the guard from the linkage, permitting the 50 guard to swing freely forwardly to a position 55 which causes actuation of the translation motor in the press closing direction. When the pressing elements reach registering position the linkage is moved into latching relation with the guard, which is still in its forward position. Thereafter, operator-controlled means actuates the linkage in the opposite direction, which by its connection to the guard moves the guard into retracted position to cause press opening operation of the translation motor, and by its connection to arm 51 actuates the control means for causing operation of the reciprocation motor in press opening direction.

The detailed control mechanism I have chosen to illustrate comprises a guard 54 extending substantially the entire length of the buck. The guard shown is made up of bars 55 rigidly joined and having rigidly connected, upwardly extending arms 56 by which it is pivotally suspended from brackets 57 connected with the frame. Stop 75

members 58 on the brackets limit the forward movement of the guard. A post 59 and a rod 60 connect the guard with the lever 61 which actuates the inlet valve 62 and exhaust valve 63 which, in turn, control the flow of the fluid medium from the main supply line 64 through the conduit 65 to translation cylinder 20.

5 The coupling means by which the guard is connected to the cam and follower combination 53, 10 58 is as follows. A bracket 66 on the guard carries a pin 67, over which is hooked the end of link 68. The linkage includes bell crank 69, link 70, bell crank 71, and link 72 which is connected with control arm 51. The linkage is therefore 15 adapted to move link 68 forward when the arm 51 moves in a clockwise direction.

For opening the press when the parts are in 20 the position of Fig. 2, I provide means for simultaneously actuating the controls of both fluid 25 motors in the press opening direction. To this end I have shown a release cylinder 73 having a piston rod 74 adapted to rotate release lever 75 in a counter-clockwise direction. Fluid pressure is supplied to the release cylinder through 30 release valve 80 suitably mounted within reach of the operator, thence through conduit 81. Check valve 82 prevents flow of the fluid from conduit 81 beyond that point. The release lever 35 impinges on bell crank 71 and thus, through the aforementioned linkage pulls the guard 54 to retracted position and at the same time moves control arm 51 in a counter-clockwise direction. The arm 51 thus causes valve 48 to close and valve 49 to open whereupon piston 45 falls due to the 40 weight of the parts. The movement of the guard to retracted position causes lever 61 to close valve 62 and open valve 63 thus exhausting cylinder 20 and permitting spring 31 to return the buck to its outer position.

Upon the guard is mounted a control lever 45 in the nature of an unlatching device for unhooking the link 68 from the pin 67. This is best 50 seen in Figs. 4 and 5 where two such levers are shown. The lever 76 is used for the individual 55 press operation just described. This lever is pivoted on pin 67 and carries a pin 77 adapted to contact link 68 and raise it clear of pin 67 to permit the guard to swing to the right as viewed in Fig. 5. The lower surface of the end of link 68 is extended as at 68' so that the link will be supported in its raised position with the surface 68' resting on pin 67 until the parts are moved to again hook the end of link 68 over the pin 67. The other lever 78 is used when two presses are operated in tandem. It carries a pin 79 for the same purpose as pin 77.

The control mechanism for tandem operation 60 is the same as that already described, save that control lever 78 is used instead of lever 76 and release valve 80 is not used. The release lever 75 of one press is actuated from another press by arranging a valve to supply air to the release cylinder 73a of a second press through conduit 83a at the same time that lever 61 of the first press is actuated in press closing direction. The 65 mechanism shown comprises an additional valve 84 adjacent valves 62 and 63. This valve 84 is actuated through rod 85 connected with lever 78 and admits air from the main supply line 64 to conduit 86 which communicates through conduit 66a and check valve 62a with the release cylinder 73a of the second press. Thus the second press is opened at the same time the first press is closed.

In Fig. 6 are shown in a diagrammatic manner 70 the connections between two presses for cross tan-

dem operation. The parts are numbered according to the description of the single press except that the reference characters on the second press have the suffix "a".

The operation of the press is as follows:—

With the parts in the position of Fig. 1, the operator arranges the lay of the work on the buck 13. She then pulls the control lever 76 for individual press operation (or 78 for tandem operation). Pin 71 (or 79) lifts link 68 from pin 67. Guard 54 swings forward, pulling rod 60, which, through lever 61, closes valve 63 and opens valve 62. Fluid under pressure flows from main line 64, through conduit 65 to cylinder 20 moving piston 22 and piston rod 23 to the right, 15 as seen in Fig. 1. Links 26 and 27 rotate shaft 28 counterclockwise, and the shaft, in turn, through links 29 and 30, moves carriage 14 and buck 13 horizontally along rails 16 until stop 40 contacts boss 41, such translatory movement being cushioned by snubber 36 through links 37, 38 and 39. If the operator's hands contact guard 54, lever 61 is reversed and the buck returns to its outer position.

Until the buck registers beneath the head, following 25 lower 53 travels along the lower edge of cam 18. Upon reaching registering position, follower 53 enters notch 19, control arm 51 rotates clockwise, opening valve 48, closing valve 49 and admitting fluid pressure beneath piston 45. The rod 46 contacts stem 17 on the buck and closes the press. When arm 51 moved clockwise it moved bell cranks 71 and 69 in the same direction and moved link 68 forward until it again hooked over pin 67. The parts are now in the position of Fig. 2.

When sufficient time has elapsed to complete the pressing operation, the operator admits fluid pressure to cylinder 73, either through valve 80, or, in tandem operation, through valve 84a of the other press. Rod 74 rotates release lever 75 and bell crank 71 counter-clockwise. Link 72 moves control arm 51 counter-clockwise, closing valve 48 and opening valve 49. Piston 45 falls due to the weight of the parts and the buck is lowered from the head. At the same time bell crank 71, through link 70, bell crank 69, link 68, pin 67, bracket 66, link 59 and rod 60, reverses the lever 61, thus closing valve 62, opening valve 63, exhausting cylinder 20, and permitting spring 31 through crank 32, shaft 28 and links 29 and 30 to return the buck to its outer position. This horizontal movement of the buck is again cushioned by the double-acting snubber 36.

The manner of exhausting release cylinder 73 will be understood from an inspection of Fig. 6. It will be noted that the stem of valve 80 fits loosely in the valve body at 91. This is so arranged that it does not prevent the building up of pressure in cylinder 73, but permits a slow exhaust therefrom.

What I claim is:

1. In presses of the class described, the combination of two presses, each having coacting pressing elements, one of which is movable toward and from the other, fluid power means for moving the movable element, inlet and exhaust valves for controlling the fluid supply to the power means, and each press having an actuator movable in one direction for opening the inlet and closing the exhaust valve and movable in another direction for closing the inlet and opening the exhaust valve, and one control member having operative connections with both actuators for simultaneously controlling movement of the ac- 75

- tuator of one press in one direction and movement of the actuator of the other press in the other direction.
2. In a press of the class described, the combination of a stationary head, a buck movable out of registration with said head, a fluid motor adapted to move the buck into registering position, control means therefor, means for moving the buck out of registering position, a second fluid motor adapted to close the press, control means therefor, and means for actuating both control means in press opening and out of registration direction substantially simultaneously.
3. In a press of the class described, the combination of a stationary head, a buck movable into and out of registration with said head, a fluid motor adapted to move the buck into registering position, control means therefor, means for moving the buck out of registering position, a second fluid motor adapted to close the press, control valves therefor, control means for said valves including mechanism adapted to cause actuation of the valves in a press closing direction when the buck is in registering position, and one operating member for effecting the movement of both control means in press opening and out of registration direction.
4. In a press of the class described, the combination of a stationary head, a buck movable into and out of registration with said head, a fluid motor adapted to move the buck into registering position, control means therefor, means for moving the buck out of registering position, a second fluid motor adapted to close the press, control valves therefor, control means for said valves including mechanism adapted to cause actuation of the valves in a press closing direction when the buck is in registering position, and coupling means between the two control means, there being a member acting on the coupling means to operate both control means in press opening direction.
5. In a press of the class described, the combination of a stationary head, a buck movable out of registration with said head, a fluid motor adapted to move the buck into registering position, control means therefor, means for moving the buck out of registering position, a second fluid motor adapted to close the press, control means therefor, a guard member adapted upon movement in one direction to move the first named control means in registration-producing direction and upon movement in another direction to move the same control means in out-of-registration-producing direction, said member being arranged to be moved in the second named direction by an operator's hand lying on the buck during the movement into registration producing position.
6. In a press of the class described, the combination of a stationary head, a buck movable out of registration with said head, a fluid motor adapted to move the buck into registering position, control means therefor, a second fluid motor adapted to close the press, control means therefor, coupling means between the two control means, said coupling means being arranged to move both control means in press opening and out-of-registration direction, and said coupling means including a guard member adapted in one position to move the first named control means in registration-producing direction, said guard member being disconnected from the rest of the coupling means upon initiation of movement of
- the first-named control means in registration-producing direction and being automatically reconnected with the coupling means when the buck reaches registering position.
7. In a press of the class described, the combination of a stationary head, a buck movable out of registration with said head, a fluid motor adapted to move the buck into registering position, control means therefor, a second fluid motor adapted to close the press, control means therefor, coupling means between the two control means, said coupling means being arranged to move both control means in press opening and out-of-registration direction, said coupling means including a guard member adapted in one position to move the first named control means in registration-producing direction and in another position to move the same control means in out-of-registration-producing direction, said member being arranged to be moved into the second named position by an operator's hand lying on the buck during the movement into registration, said guard member being disconnected from the rest of the coupling means upon initiation of movement of the first named control means in registration-producing direction and being automatically reconnected with the coupling means when the buck reaches registering position.
8. In a press of the class described, the combination of a stationary head, a buck movable out of registration with said head, a fluid motor adapted to move the buck into registering position, control means therefor, means for moving the buck out of registering position, a second fluid motor adapted to close the press, control valves therefor, control means for said valves including mechanism for causing the operation of said valves in a press closing direction when the buck is in registering position, coupling means between the two control means, said coupling means being arranged to move both control means in press opening and out-of-registration-producing direction, said coupling means including a guard member adapted upon movement in one direction to move the first named control means in registration-producing direction and upon movement in another direction to move the same control means in out-of-registration-producing direction, said guard member being disconnected from the rest of the coupling means upon initiation of movement of the first named control means in registration producing direction and being automatically reconnected with the coupling means by movement of said valve control mechanism when the buck reaches registering position.
9. In presses of the class described, the combination of two presses each having a stationary head, a buck movable out of registration with said head, a fluid motor adapted to move the buck into registering position, control means therefor, means for moving the buck out of registering position, a second fluid motor adapted to close the press, control means therefor, coupling means between the two control means, and there being a fluid pressure actuated member acting on the coupling means to operate both control means in press opening and out-of-registration direction, the fluid pressure actuated member of one press being operatively connected with the control means for the first named fluid motor of the other press.
10. In combination, two presses each having a buck member and a head member adapted to move into and out of registration with each

other, power means to move one of the members to effect registration, control means for said power means, manual means for controlling the movement of the control means in registration-producing direction and power means for actuating the control means in out-of-registration-producing direction, there being manual means for controlling the second named power means, and the first named manual means of one press 10 and the second named manual means of the other press being located at a common point.

11. In a press of the class described, the combination of a frame, a stationary head carried by the frame, a carriage movable horizontally along the frame from and into registration with said head, a buck supported on the carriage for limited substantially vertical movement relative thereto, fluid motor means for moving said carriage horizontally and for moving said buck substantially vertically relative to said carriage, when said carriage is in registration beneath said head, a valve for controlling the means for moving said buck vertically, and a bar on said carriage for controlling said valve when the carriage and buck register with the head.

12. In a press of the class described, coacting pressing members, one of which is movable laterally into and out of registration with the other, power mechanism for actuating the movable member, control means for said mechanism, a guard movably mounted adjacent the path of travel of said member, and an operative connection between said guard and said control means operable by movement of said guard in the direction of the into-registration movement of the movable member to actuate said control means in out-of-registration-producing direction.

13. In a press of the class described, the combination of a pair of coacting pressing members, one of which is movable into and out of registration with the other and movable into pressure engagement therewith, a fluid pressure actuated motor for causing each of said movements, control means for each motor, and fluid pressure responsive means for actuating both control means in press-opening and out-of-registration direction.

14. In a press of the class described, a stationary head member, a bed movable into and out of registration therewith, fluid pressure actuated means for moving said bed, control valves therefor, and control mechanism for said valves including a fluid actuated release means, a manual actuator therefor, a finger guard adjacent the head, an operative connection between said release means and guard, and an operative connection between said guard and valves.

15. In combination, two presses each having coacting pressing members adapted to move into and out of registration with each other, power means for moving one of said members to effect registration, control means for said power means, a guard adapted to actuate the control means in registration-producing direction when the guard is moved into guarding position, power means for actuating the control means in out-of-registration-producing direction, control means for the second named power means, and a single control member having operative connections for controlling the movement of the guard of one press

into its guarding position and for simultaneously actuating the last named control means of the other press.

16. In a press of the class described, the combination of a pair of coacting pressing members, one of which is fixed and the other movable into and out of registration therewith and into and out of pressure engagement therewith, a fluid pressure actuated motor for moving said movable member into registration, control means 10 therefor, a movable guard depending before said fixed member and having connection adapted to actuate said control means in out-of-registration-producing direction, a second fluid motor for moving said movable member into pressure 15 engagement, control valves for said second motor actuatable in into-pressure-engagement-producing direction upon movement of the movable member into registration, a release device, and an operative connection between said release device and said valves for actuating the valves in out-of-pressure-engagement-producing direction.

17. In presses of the class described, the combination of two presses each having coacting relatively movable pressing members, fluid pressure 25 actuated power means for moving one of said members, control valves for said power means, and two actuators for said valves; means operable by one of said actuators for causing movement of said valves of said one press in a direction to cause a closing movement of said one press, and means operable by the other actuator of the said one press for causing movement of said valves of said one press to cause a closing movement of the said one press and for simultaneously causing movement of said valves of the other press to cause opening thereof.

18. In a press of the class described, coacting pressing members, one of which has translatory and reciprocatory motion with respect to the other, a motor for causing each motion, separate control means for each motor, mechanism for causing actuation of the control means for the reciprocation motor in press-closing direction after the translation motor has moved the members to registering position, and a common release member for moving both control means in press-opening and out-of-registration direction.

19. In combination, two presses each having coacting pressing elements one of which is movable toward and from the other, fluid power means for moving the movable element of each press, inlet and outlet valves for controlling the fluid supply to each power means, each press having an actuator movable in fluid supply direction for opening the inlet and closing the outlet valve and movable in fluid exhaust direction for closing the inlet and opening the outlet valve, each press having two control members selectively operable by the operator, one control member having an operative connection with the actuator of one press for moving the same in fluid supply direction, and the other control member having two operative connections, one with the actuator of one press for moving the same in fluid supply direction and the other connection with the actuator of the other press for moving the same in fluid exhaust direction.
